DESIGN FOR A BRACELET

Emil J. Ostheimer, Woodside, Long Island, N. Y.

Application October 9, 1946, Serial No. 133,851

Term of patent 7 years

(Cl. D45—4)

To all whom it may concern:

Be it known that I, Emil J. Ostheimer, a citizen of the United States, residing at Woodside, Long Island, in the county of Queens and State of New York, have invented a new, original, and ornamental Design for a Bracelet, of which the following is a specification, reference being had to the accompanying drawing, forming a part thereof.

In the drawing:

Fig. 1 is a front elevational view of a bracelet showing my new design, portions thereof being broken away for illustrative purposes as indicated by the dotted lines.

Fig. 2 is a top plan view of the same; and

Fig. 3 is a fragmentary rear elevational view taken in the direction of the arrows 3—3 of Fig. 2.

I claim:

The ornamental design for a bracelet, as shown and described.

EMIL J. OSTHEIMER.
